DISPENSER FOR DRINKING STRAWS

Theodore R. Reece, Calgary, Alberta, Canada

Application July 20, 1950, Serial No. 174,905
In Canada August 8, 1949

1 Claim. (Cl. 312—78)

1

My invention relates to a dispenser for drinking straws, and has for its object the provision of a ready means for handily ejecting only one such straw at a time, and ejecting it just sufficiently so that it may be conveniently withdrawn from the top of a straw container.

An advantage in my invention is that the unit is thoroughly hygienic, since the ingeniousness of the device permits only a single straw to be handled at a time by a person, and that in this process it is not a matter of selecting a straw at random from a bundle of straws but prevents the possibility of contamination from careless fingering of the straws.

A further advantage is that the straw container is transparent providing visibility of the straws in attractive colors, and for purposes of replenishing the container with straws.

A still further advantage is that once a single straw is partly ejected from the container and ready for use means are provided to keep the straw in its raised position after the ejecting mechanism is released, and at the same time it may be pushed down into the container ready for ejection again.

The mechanism for operating the ejection of a straw is of very simple construction requiring few parts, and it is manipulated in an attractive manner, and needs no instructions.

The preferred material for the container and its cover is plastic or other similar composition readily moulded and shaped, and which may be accurately fabricated, and is semi-unbreakable and transparent, such features being essential when in use on restaurant and other counters for handling by the public.

Although this invented straw dispenser is susceptible of modifications as to shape, it is unnecessary to fully describe and illustrate more than one in order to give a full understanding of the invention both from its shape and functional standpoints. Accordingly I have illustrated a preferred and desirable embodiment of the invention in the accompanying drawings forming part of this specification, and throughout the views of which like reference characters refer to the same parts.

Fig. 1 is a fragmentary partly sectionalized view of the dispenser.

Fig. 2 is a plan view with cover and straw-supporting disk removed, and only a fragmentary portion of the base shown.

Fig. 3 is a cross sectional view of the cover and the annular ejection port.

Fig. 4 is a cross section on line 4—4 of Fig. 2.

2

Fig. 5 is an end view in elevation of the block supporting the ejection mechanism.

In the drawings the numeral 1 refers to a cylinder preferably made of transparent plastic or similar material, for containing a number of drinking straws or tubes 1a. This cylindrical straw container has a removable cover or lid 2, and it rests on a base plate 3, and is maintained securely in an upright position by means of two or more block members 4 on the base plate over which blocks the bottom open end of the container fits and is fastened thereto by screws 5 as seen in Fig. 1.

A loosely fitting straw-supporting disk 6 is disposed within the container 1 at a little more than a straw length from the cover 2. A ring 7 is affixed to the inside face of the container, and a second ring 8 is similarly affixed to the inside face of the container above said ring 7 in spaced relationship therewith between which rings the disk 6 may be loosely agitated as later described.

Inside the lower portion of the container 1, and immediately below the disk 6, is a block member 9 for supporting the disk 6 and straw lifting means as here described. This block member is divided into two vertical halves, and is apertured therebetween from top to bottom to receive a slideable metal plunger 10 pointed at its upper end at 11 and slotted vertically at its lower end at 12. This plunger is the straw lifting element when made to rise, as later described.

The disk 6 is of special cross section shape, and instead of being flat is graded gradually and uniformly downwardly from the outer peripheral edge to the center thereof, which center is apertured for the passage of the plunger 10, and is shaped to form a downwardly protruding neck 13. It is due to the declination of the upper face of the disk 6 of approximately four to six degrees from a horizontal plane towards the center that the straws tend to bunch together towards the center of the plate, as a result of which one straw will always find its way to the center aperture and in position on the plunger point for raising thereby.

The same principle is adopted as regards the shape of the cover 2. This cover is inclined upwardly from its periphery towards the center thereof, which center is apertured for the ejection therethrough of the ejected straw. An annular ring 14 is affixed above this aperture at the apex of the cover, in which ring short lengths of rubber 15 (Fig. 3) are inserted which

project inwardly into the aperture. These pieces of rubber are to frictionally retain a straw of any diameter for holding same in its ejected position. The cover 2 is recessed at 16 peripherally for proper fitment on the top of the container 1.

In order to effect the raising action of the plunger 10 for ejecting a straw, a finger-manipulated lever 17 is fulcrumed on a pivot pin 18 mounted in and between two pedestals 19 attached to the base plate 3 exteriorly of the container 1, and extends through slots 20 in the base end of the container, and through the said slot 12 in the plunger 10. Hand pressure on the extending end 17a of this long lever 17 will therefore raise the plunger 10 together with a straw on its top pointed end, and thus the straw will be ejected a distance sufficient for drawing out by hand. The lever 17 descends automatically on release, and the straw remains above the cover unless later pushed down.

Cross pieces of plastic 21 are for securing the two halves of the block 9 together. A tappet rod 22 is made to strike the underneath face of the disk 6 in a more or less vibratory manner by means of a lever 23 swingably pivoted within a slot 24 in the base of the block 9. This rod reciprocates freely through a vertically holed passageway in the block and is weighted at 25 at its top end, and rests on one short arm of the lever 23. The other longer arm of this lever 23 is lowered by plunger 10 as the long arm of lever 17 is lowered to rest. As soon as this lever 17 is raised the weighted rod 22 depresses the short arm of lever 23. Consequently there is a slight knocking effect by this rod 22 on the disk 6 to agitate the straws thereon, and by this means is assured a positive movement of straws towards the center of the disk 6, one of which straws will gravitationally enter the center aperture of the disk as mentioned.

It is to be understood that any slight modifications in the shape of the various parts of this device will not change the spirit and scope of the following claim.

What I claim and desire to secure by Letters Patent:

In a drinking straw dispensing device as de-

scribed, of the vertical straw-container type, to hold a plurality of tubular drinking straws for single straw-dispensing, and with a dome-shaped cover having a straw-passaging central aperture therethrough, resilient and flexible straw-retaining and straw-restraining bars projecting more or less horizontally into said aperture for suspension of any sized tubular drinking straw following its partial ejection therethrough, a straw-carrying disk dished slightly downwardly towards its center, and fitting loosely within the container in a more or less horizontal position, an apertured neck in the center of said disk projecting downwardly, and resting normally on a means of support within the straw container, a pair of rings fitted peripherally within and around the interior of the container between which the said disk is spaced disposed and on the lower of which rings it would also normally rest, plunger means in association with hand-manipulating lever means operating to dispense a straw upwardly from said apertured neck and partially through said cover aperture, a weighted tappet rod for agitation of said disk and slideable through a vertical aperture within the neck-supporting means, and a tappet rod operating lever pivotally supported on the said means of support within the straw container, its shorter arm supporting the tappet rod, and its longer arm being contacted by the gravitationally falling plunger means to agitate the said disk by the tappet rod for centralizing a single straw.

THEODORE R. REECE.
